(74) **Attorney, Agent, or Firm:** Wenderoth, Lind & Ponack, L.L.P.

(57) **CLAIM**

The ornamental design for a tape feeder, as shown and described.

DESCRIPTION

FIG. 1 is a first perspective view of a tape feeder, showing our new design;

FIG. 2 is a second perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial view thereof, taken along the intersection of lines 9-9 of FIG. 1; and,

FIG. 10 is a partial view thereof, taken along the intersection of lines 10-10 of FIG. 8.

The dash broken lines in the drawings illustrate portions of the tape feeder which form no part of the claimed design. The dot-dash broken lines illustrate boundaries which form no part of the claimed design. The dot-dot-dash broken lines illustrate section lines which form no part of the claimed design.

1 Claim, 10 Drawing Sheets
